CLAIM

I claim the ornamental design for dehydrator with top mounted control, as shown and described.

DESCRIPTION

FIG. 1 is a top, right perspective view of a dehydrator with top mounted control of the present invention.

FIG. 2 is a front view of the dehydrator with top mounted control depicted in FIG. 1;

FIG. 3 is a left side view of the dehydrator with top mounted control depicted in FIG. 1;

FIG. 4 is a rear view of the dehydrator with top mounted control depicted in FIG. 1;

FIG. 5 is a right, side view of the dehydrator with top mounted control depicted in FIG. 1;

FIG. 6 is a top view of the dehydrator with top mounted control depicted in FIG. 1;

FIG. 7 is a bottom view of the dehydrator with top mounted control depicted in FIG. 1;

FIG. 8 is a bottom, left perspective view of the dehydrator with top mounted control depicted in FIG. 1;

FIG. 9 is a top, right perspective view of a dehydrator with top mounted control of the present invention shown in an alternate configuration;

FIG. 10 is a front view of the dehydrator with top mounted control depicted in FIG. 9;

FIG. 11 is a rear view of the dehydrator with top mounted control depicted in FIG. 9;

FIG. 12 is a right side view of the dehydrator with top mounted control depicted in FIG. 9;

FIG. 13 is a left side view of the dehydrator with top mounted control depicted in FIG. 9;

FIG. 14 is a top view of the dehydrator with top mounted control depicted in FIG. 9;

FIG. 15 is a bottom view of the dehydrator with top mounted control depicted in FIG. 9;

FIG. 16 is a bottom, left perspective view of the dehydrator with top mounted control depicted in FIG. 9; and,

FIG. 17 is a top, right perspective view of the dehydrator with top mounted control of FIG. 1 with components illustrated as separated apart to provide a clearer view of the ornamental aspects of the design.

The broken lines in the Figures illustrate portions that form no part of the claimed design and may depict environmental subject matter only.
